UNITED STATES PATENT OFFICE.

ENOCH SMITH, OF SALT LAKE CITY, UTAH, ASSIGNOR OF ONE-THIRD TO
GEORGE CURLEY, OF SALT LAKE CITY, UTAH.

DUMPING-WAGON.

No. 823,554.

Specification of Letters Patent.

Patented June 19, 1906.

Application filed May 2, 1905. Serial No. 253,449.

To all whom it may concern:

Be it known that I, ENOCH SMITH, residing at Salt Lake City, in the county of Salt Lake and State of Utah, have invented certain new and useful Improvements in Dumping-Wagons, of which the following is a specification.

My invention relates to certain new and useful improvements in wagons; and it more particularly relates to that class of wagons known as "dumping-wagons," in which means are provided for quickly and effectively unloading wagons whenever found desirable.

My invention has for its object to provide a wagon of this class of a very simple and economical construction in which all of the operating parts are compactly arranged and in which all of the parts of the wagon are of a durable construction, which wagon will readily and effectively serve its intended purposes.

Generically my invention comprises a wagon, including a body portion, wheels upon which the body portion is mounted, and a plurality of trap-doors arranged when closed to form the bottom of the wagon, and means under control of the driver for releasing said trap-doors to open the wagon-bottom to permit the exit of the contents of the wagon.

With other objects in view than have heretofore been enumerated the invention also comprises a novel construction and detail arrangements of parts, all of which will be first described in detail, then specifically pointed out in the appended claims, reference being had to the accompanying drawings, in which—

Figure 1 is a perspective view showing my invention as applied for use, the trap-doors forming the wagon-bottom being open. Fig. 2 is a side elevation of the wagon. Fig. 3 is an inverted plan view thereof. Fig. 4 is a top plan view of the front end of the wagon. Fig. 5 is a cross-section on the line 5 5 of Fig. 2 looking in the direction of the arrow. Fig. 6 is a horizontal section on the line 6 6 of Fig. 5. Fig. 7 is a detailed section on the line 7 7 of Fig. 3. Fig. 8 is a similar view showing a slightly-modified construction of my invention, showing the door construction for sheet-metal wagon-bodies. Fig. 9 is a detailed view of a further modification hereinafter specifically referred to. Fig. 10 is a detail diagrammatic view hereinafter specifically

referred to. Fig. 11 is a detail view of the beams 10 10^a and their attached parts. Fig. 12 is a detail view of the bearing for the hinge rod or pipe 32^x.

Referring now to the accompanying drawings, in which like numerals and letters of reference indicate like parts in all of the figures, it will be seen that the wagon comprises a body 1, including the sides 2 2, the rear gate 3, and the front wall or end 4.

5 5 designate cross-beams arranged across the wagon-body beneath the same, to which the wagon-body is secured by brace or stay rods or bars 5^a 5^a 5^b 5^b, as shown. 6 designates another cross-beam secured to the wagon-body by stay bars and braces 6^a 6^a 70 and 6^b, which beam 6 is secured to the rear axle-beam 7 by any suitable means desired, braces 8 being provided to strengthen such connection.

At the front of the wagon and under the seat 9 I secure below the wagon-body a pair of cross-beams 10 10^a, which are bolted or otherwise secured to the spacing-blocks 11 11, as shown. Secured to the beams 10 10^a at the middle thereof on the under side is the upper fifth-wheel member 12, which has a central stud 12^a to project into the central aperture 13^a of the lower fifth-wheel member 13, which member 13 is secured to the draft-block 14, as shown. The draft-block 14 is in turn secured to the axle-beam 15 of the front axle.

The lower fifth-wheel member 13 has its aperture 13^a provided with a supplemental radial aperture portion 13^b to permit passage of the lug 12^b of the stud 12^a, which when the members 12 and 13 are turned into proper position serves to interlock the said members.

The tongue 16 is secured to the draft-block 14 by a bolt 16^a, while the equalizing-bar or "doubletree" 17 is pivotally secured to the tongue and draft-block 14 by the bolt 16^a and the chains 18 18 on top of the block 14, thus relieving the horses of all weight other than that of the tongue end.

The beam 10 is provided at one side with a vertical pulley 19, and on its under side adjacent the pulley 19 the beam 10 is provided with a second pulley 20, arranged horizontally for co-operation with a similarly-arranged pulley 21 on the under side of the beam 10^a. The beam 10^a is also provided

with a vertical pulley 27 near its other end and diagonally opposite to the pulley 19 for a purpose presently explained.

At the front portion the wagon is provided 5 with a platform 1^x, to the under side of which the brake-lever 22 is pivoted, as at 22^a. Secured to the brake-lever 22 at any suitable point is a brake-chain 23, which is adapted to be wound around the lower end 24^a of a vertically-mounted brake turn-rod 24. The rod 24 is mounted on the platform 1^x and braced by suitable stays 25 25, as shown, and the said rod 24 has a ratchet 24^b, that coöperates to hold the rod in its adjusted position, 15 a hand-wheel 25 being provided at the upper end of the turn-rod 24, whereby the rod 24 can be manipulated.

Pivotedly mounted in bearings on the wagon-body is a U-shaped rod 26, which 20 carries the brake-shoes 27 27 at its free end, which brake-shoes 27 27 are adapted to engage the rear wheels W W of the wagon. Secured to the rod 26 at a suitable point adjacent to one of the brake-shoes is a cable 28, 25 which passes over idler-pulleys 29 and 30 on one side of the wagon-body and connects with the brake-lever 22 at a point to one side of its pivot, as shown. A similar cable 28^a is connected to the lever 22 at a point on the 30 other side of its pivot and passes over idler-pulleys 29^a 30^a on the other side of the wagon-body and connects with the rod 26 near the other brake-shoe. When the brake-chain 23 is wound up on the rod 24, the cables 28 and 35 28^a are tightened and the brake-shoes 27 27 applied to the wheels to stop the wagon.

32 32 designate a plurality of trap-doors which when closed together form the bottom of the wagon, and the doors 32 are hinged to 40 the beams 5 5 and 6, a cross-bar 32^a being provided for each door 32 and extending across its front edge on the under side thereof, the said bar 32 projecting beyond the sides of the wagon for a purpose presently explained.

33 designates chains which are connected to one end of the doors 32 and pass over idler-pulleys 34 34 on one side of the wagon. The chains 33 connect with a main chain 35, 50 which passes over idler-pulleys 36 on the wagon-body and which passes over the idler-pulley 19 on the beam 10 and connects with the dump-chain 37, which chain 37 is adapted to be wound around the lower end 38^a of a vertically-held turn-rod 38, which is mounted on the platform 1^x. The rod 38 is held by suitable brace-stays 39 and is provided with a ratchet 40, which coöperates with a pawl 41, as clearly shown in Fig. 4, a hand-wheel 60 42 being provided on the upper end of the rod 38, by means of which the said rod can be manipulated.

33^a 33^a designate chains similar to chains 33, which are joined at one end to the front 65 end of the cross-bars 32^a of the door 32 and

which pass over idler-pulleys 34^a on the other side of the wagon, located similarly to those 34 on the opposite side of the wagon, a chain 33^a connects with the main chain 35^a, which passes over idlers 36^a on the side of the wagon 70 opposite to that on which the idlers 36 are disposed, and the chain 35^a passes over the idler-pulley 32 on the beam 10^a and over the idler-pulleys 21 and 20 and connects with the dump-chain 37.

75 By turning the rod to which the dump-chain is connected and winding the said chain up on the said rod the chains 35 and 35^a are tightened up and the doors 32 are held closed. By releasing the dump-chain 37 the chains 80 35 and 35^a are loosened to permit the doors 32 dropping to the position shown in Fig. 1 to allow the contents of the wagon to be dumped out.

In Fig. 9 I have shown a slightly-modified 85 form of my invention which is particularly adapted for use when the wagon-body is composed of metal, and in this form the door-body is constructed of sheet-iron and is secured to a tubular pipe-hinge 32^x by the 90 hinge-straps 32^y, as shown, a flat bar 32^m being secured to the front edge of the door 32 to overlap the adjoining door to form a tight closure between adjacent doors and forming, when the doors are closed a practically continuous bottom. The pipe portion 32^x which passes through the straps 32^y is held at its ends in bearings 32^z at the wagon sides. (See Fig. 12.)

95 From the foregoing it will be seen that I 100 have provided a very simple and economically-operatable wagon in which the brake and dumping devices are so arranged as not to interfere with the operation of each other, and from the foregoing description, taken in 105 connection with the accompanying drawings, it is thought the complete construction, operation, and many advantages of my invention will be readily understood by those skilled in the art to which it appertains, and 110 while I have shown my invention so arranged that all of the bottom gates are opened simultaneously, yet, as shown in Fig. 10, I may provide hooks for the chains 33 and 33^a, which 115 can be hooked onto the said chains to independently hold the doors shut, so that when the main chain is released only those doors are opened which are not hooked up, thus allowing the doors to be opened independently of each other.

120 I make no claim to the specific construction of brake mechanism *per se* disclosed in this invention nor to the specific construction of fifth-wheel in this case, as the same form the subject-matters of copending applications.

Having thus described my invention, what I claim, and desire to secure by Letters Patent, is—

1. In a dumping-wagon, a body consisting 130
